Inventor:
Harold G. Tregillus,
By Harvey L. Hanson, Attorney.

UNITED STATES PATENT OFFICE.

HAROLD G. TREGILLUS, OF PARK RIDGE, ILLINOIS.

TRUSSSED STRUCTURE.

Original application filed June 23, 1920, Serial No. 391,035. Divided and this application filed January 8, 1925. Serial No. 1,306.

My invention refers to trussed structures of the class disclosed in my Patent No. 1,380,771, of February 10th, 1920, the object of the invention being to provide modified 5 truss formation which will better adapt the trussed structures to varying conditions encountered in actual practice, while at the same time increasing the efficiency and permitting the structures to be built with 10 greater economy.

This application is a division of my co-pending application, Serial No. 391,035, filed June 23, 1920, for improvement in trussed structures.

15 In the form shown in the patent referred to, the anchoring or tension members extend from the ends of the arch member to intermediate points thereof, that is, the ends of the arch form the anchorage points for 20 the anchoring members. Under certain conditions it may be desirable to change the location of the anchorage point or points. For example, where the span is so long that the stock material for the anchoring members would not be long enough, it would be 25 desirable to shift the anchorage points to permit the use of shorter anchoring members. Under other conditions, it might also be desirable to shift the anchorage points 30 away from the ends of the arch or truss. In the structure of my patent above referred to, we have an inverted Bollman truss structure associated with an arch member and with this arrangement the anchorage points 35 are at the arch ends. By changing the form of the inverted truss structure, the anchorage point or points, i. e., the point or points of application of the arch retaining tension members, can be shifted from the arch ends 40 to some intermediate point or points on the truss structure and such shifting of the anchorage points will permit the use of shorter tension members for connecting the point or points of anchorage with the arch.

45 The structure of which the shifted anchorage points form a part, I call the inverted truss structure or formation, and the combination of this inverted truss formation with the arch member and the tension members I call the trussed structure.

In operation, then, the inverted truss formation is anchored to the arch ends, and intermediate points on the arch are anchored to a predetermined anchorage point, or pre-determined anchorage points on the chord

member of the inverted truss formation by means of tension members.

On the accompanying drawing, my invention, is incorporated and illustrated in a trussed structure showing modified inverted 60 truss formation. In this drawing,

Figure 1 is a side elevational view of one form of structure.

Figure 2 is a sectional view on line 2—2, 65 Figure 1.

Referring to Figure 1 the trussed structure shown comprises the arch member 10, tension members 11 and an inverted truss formation to which the arch member is anchored by the tension members. The inverted truss formation or structure shown comprises the chord member 12, the inverted truss tension members 13 and 14 and the strut member in the form of a king-post 15 connecting between the juncture of the truss 70 tension members and the chord member 12. As shown in Figure 2 the arch member may be composed of two angle bars *a*, and the chord member 12 may be composed of two angle bars *b*, while the strut member may 75 be composed of two angle pieces *c* secured at their upper ends to plate *d* and at their lower ends to plates *e*, the plate *d* being secured to the arch member bars *a* and the plates *e* being riveted to the chord member 80 bars *b*. The chord and arch members are connected together at their ends by web plates *f* and *g* to which the truss tension members 13 and 14 are also secured, the inner ends of these members being secured to 85 the plate *d*. The truss structure is thus connected directly to the arch member at the ends and center thereof. The plates *e* form an anchorage for the tension members 11 which radiate therefrom and connect with 90 the arch member at intermediate points thereof. The principle of operation of this trussed structure is the same as that disclosed in my patent referred to, the tension members together with the truss formation 95 preventing bulging of the arch member during application of irregular load thereto, and consequently preventing flattening of the arch member at other points.

Primarily the anchorage points are at the 105 ends of the arch which are held properly spaced by the chord member 12 which becomes the tension chord of the trussed structure when under load. By means of the truss formation or structure extending between the 110

arch ends, the anchorage points can be shifted to any desired location on the truss structure. In Figure 1, the shift has been made to the center of the chord member 12, and owing to the rigid truss formation the point of anchorage represented by the plates *e* is positive. By thus shifting the anchorage much shorter tension members 11 can be used, and there are many advantages in the use of such shorter tension members.

In the structure shown on the drawings of my patent, the arch retaining members form necessary parts of the inverted Bollman truss structure, while in the arrangement of this application the inverted truss is a structure complete in itself, arch retaining members radiating to the arch member from selected points of anchorage on the truss. In the structure shown on the drawings of the patent, the inverted Bollman truss formation comprises only tension members, while in the arrangement disclosed in this application the truss formation comprises both tension and compression members.

In order that the term "inverted" as applied to the truss formation shall be clearly understood, it is pointed out that any truss for supporting loads, that is, to resist downward forces, is not inverted and has the main tension member at the bottom. The truss formation of my invention is for resisting upward forces, and has its main tension

member at the top. It is therefore an inverted truss.

Having described my invention, I claim as follows:

1. A roof truss comprising an arch, a main chord for the same, a pair of secondary chords respectively spanning half of the arch, a strut disposed medially of the truss and connecting the arch with the main chord, and bracing means associated with each half of the truss for resisting an increased convexing of one-half of the arch by an excessive loading of the other half thereof.

2. The combination of an arch, a triangle of tension members having two of its corners directly attached to the arch ends and the remaining corner directly attached to an intermediate point on the arch, a strut joining said intermediate point on the arch and the opposite side of said triangle, and tension members joining the lower end of said strut and said arch at various points thereon.

3. The combination of an arch, a chord for the arch, two sub-chords for consecutive portions of the arch, a post joining the two sub-chords, at their juncture, to the chord, and tension members joining various portions of the arch to the post at its juncture with the chord.

In witness whereof, I hereunto subscribe my name this 7th day of January, A. D., 1925.

HAROLD G. TREGILLUS.
